(57) CLAIM

The ornamental design for a waterproof floatable container, as shown and described.

DESCRIPTION

FIG. 1 is a top, front and left side perspective view of the waterproof floatable container showing my new design, with the dotted lines being for illustrative purposes only and forming no part of the claimed design;

FIG. 2 is a top plan view thereof;

FIG. 3 is a right side view thereof (the left side being a mirror image); and,

FIG. 4 is a rear view thereof.
